UNITED STATES PATENT OFFICE.

MICHAEL W. O'BRIEN, OF ROCHESTER, NEW YORK.

EJECTING MECHANISM FOR PRESSES OR THE LIKE.

1,276,399.

Specification of Letters Patent. Patented Aug. 20, 1918.

Application filed June 27, 1917. Serial No. 177,349.

To all whom it may concern:

Be it known that I, MICHAEL W. O'BRIEN, a citizen of the United States, and resident of Rochester, in the county of Monroe and State of New York, have invented certain new and useful Improvements in Ejecting Mechanisms for Presses or the like, of which the following is a specification.

The present invention relates to ejecting mechanisms for presses or the like, and more particularly to the type which removes articles from a carrier or die after the latter has operated to carry the articles to the operating elements of the press or the like and then away from such elements. An object of this invention is to provide an ejecting mechanism which will be positive in its action so as to insure that the article will be moved away from the carrier or die in order not to be brought again between the operating elements of the press or the like. Another object of this invention is to provide a construction which will embody two ejectors, one acting to remove the article from the carrier or die, and the other to receive the article so removed and discharge it to one side of the carrier. Still another object of the invention is to provide an ejector having two members adapted to provide a chute between them to direct the articles to one side of the carrier.

To these and other ends the invention consists of certain parts and combinations of parts all of which will be hereinafter described, the novel features being pointed out in the appended claims.

In the drawings:

Figure 1 is a side view of a blank pressing machine embodying the present invention; 40 Fig. 2 is an enlarged fragmentary section through the press in the vertical plane of the axis of the rotary die or carrier;

Fig. 3 is a section on the line 3—3, Fig. 2; Fig. 4 is an enlarged detail view of the 45 mechanism for operating the secondary ejector;

Fig. 5 shows the ejecting mechanism in plan as the article is being received by the secondary ejector;

50 Fig. 6 is an enlarged section on the line 6—6, Fig. 5; and

Fig. 7 is a detail view of the ejecting mechanism showing the secondary ejector as the latter takes hold of the article.

55 The invention as herein illustrated as be-

ing embodied in a blank pressing machine of the type illustrated in Patent #1,034,493, granted to me on the 6th day of August, 1912, but it will be understood that the invention is not limited to use with a pressing machine but may be employed in any machine where an article is carried to a position to be operated by a suitable mechanism, and is then shifted away from such position.

In the illustrated embodiment of the invention, 1 indicates a frame carrying two pressing members 2 and 3, one of which is stationary, while the other is guided on a frame 1 toward and from the stationary member. Any suitable means may be employed for effecting the movement of the movable pressing member toward the stationary member, but, in this instance, the movable member has its pitman 4 operated by an eccentric 5 on a drive shaft 6 mounted on the frame 1.

Arranged to operate between the pressing members is a carrier 7 designed to carry articles between the pressing members for operation upon by said members, and then to shift the articles away from the pressing members. In this instance, this carrier 7 also acts as a die for giving shape to the articles while they are being pressed by the pressing members, as in my prior patent to which reference is herein made. Preferably this die member 7 is in the form of a flat plate with openings 8 therein shaped to conform to the desired shape of the article. In this instance, this plate is mounted to rotate, and to this end it is removably secured to one end of a shaft 9 journaled in the stationary pressing member 3 at a point to one side of the line of movement of the movable member 2, so that the pockets 8 may be successively presented between the movable pressing members 2 and 3 to permit the articles to be pressed, the articles thereafter being carried by said carrier or die plate 7 away from the movable pressing member 2. The movement of the die plate 7 is necessarily intermittent, and this is effected preferably from the drive shaft 6 which, to this end, has a beveled gear 10 thereon meshing with the beveled gear 11 on the upper end of a vertical shaft 12, which is journaled in the frame 1, and which, at its lower end, carries a gear 25 meshing with a gear 23 on a stub shaft 24. On the latter is arranged a member 13, the periphery of which is cyl-

drical, except at one side thereof where it is provided with an arm 14 extending substantially tangential to the member, and having its outer end curved on an arc of a circle, the member 13 being also provided in proximity to said arm 14 with a recess 15. The arm 14 operates between arms 16 on a member 17, said member having curved pockets 18 between the arms for receiving the arm 14 on the member 13, during the rotation of the member 13, the pocket 15 permitting the swinging of each arm 16 as the latter is engaged by the arm 14, while the cylindrical portion of the member 13 prevents the turning of the member 17 by coöperating with one of the arms 16 at the end of the latter. The member 17 is arranged on the shaft 9 to which the die member 7 is secured. It will thus be seen that the arm 14 will successively engage the arms 16, thus turning the die member 7 with a step-by-step movement, and at the same time holding said die member against movement in one direction between the different steps.

With the end in view of removing the articles from the carrier or die member 7, an ejecting mechanism is provided, which, in this instance, embodies a primary and a secondary ejector, the primary ejector removing the articles from the carrier as the articles are successively presented to said primary ejector, and the secondary ejector receiving the articles from the primary ejector and discharging them at a point removed from the carrier or die plate 7.

The primary ejector preferably embodies a plunger 19 which is guided vertically in a stationary pressing member 3 to one side of the line of movement of the movable pressing member 2, and at a point where the pockets 8 are brought to a stop after passing beyond the line of movement of the movable pressing member 2. Normally the pressing member of the ejector 19 is held out of the path of the carrier 7 by a spring 20 which, preferably, is of helical formation and surrounds the plunger ejector 19. While the carrier 7 is stationary with one of its pockets 8 over the upper end of the plunger 19, the latter is elevated by a suitable mechanism. In this instance, this is effected by a revolving cam plate 21 preferably eccentrically mounted upon a gear wheel 22, which turns freely upon the shaft 9 of the carrier 7 and is driven by the gear wheel 23 arranged on the stub shaft 24 with the member 13. It will thus be seen that the operation of the primary ejector 19 is so timed that it ejects the articles from the pockets 8 as said pockets come to rest over the upper end of the ejector.

The secondary ejector preferably embodies a member or plate 26 adapted to co-operate with that face of the article indicated at X opposite the face engaged by the

primary ejector 19, so that the article is held between the primary ejector and the member 26. While so held a pair of retaining devices 27 are moved toward each other from opposite sides of the article X at a point 70 between the article and the carrier 7, to engage with the opposite face of the article, so that when the ejector 19 lowers under the action of its spring 20, after said ejector has been released by the cam-plate 21, the article X will be supported by the retaining devices 27. The retaining devices 27 are preferably both elongated and extend when in the receiving position, from the plunger 19 to one side of the machine so that they 75 may be tilted about a horizontal axis extending transversely of the members, after receiving the article, thus acting as a chute 80 for directing the article to one side of the carrier 7. Preferably these retainers 27 85 have side flanges 28 so as to prevent the article from moving laterally from the retainers during its passage over them. The retainers, in this instance, also act to support the member 26, and to this end the 90 latter is centrally supported by the pivot 29 of a pair of cross levers 30, each of said levers being slotted at 31 at each end, and operating on a headed projection 32 on the retainers 27. This supporting means permits the retainers to move toward and from each other without decentralizing the member 26. The lugs 33 on the member 26 cooperate with the links or levers 30 to prevent the turning of the member 26 on the 95 pivot 29.

The movements of the secondary ejector are so timed that the member 26 is brought above the primary ejector 19, with the retainers 27 separated, prior to the movement 105 of the ejector 19, after which the latter shifts the article X into contact with the member 26. Then the retainers 27 move under the article X between the latter and the carrier 7. Thereafter the retainers 27 are tilted to 110 discharge the article to one side of the machine, and are then opened or separated preparatory to receiving another article.

These movements are preferably secured by mounting the retainers 27 on a rock 115 shaft 34, each retainer having a depending projection 35 on the under side mounted on the shaft 34 to turn therewith, but adapted to move longitudinally of said shaft, the shaft having a key 36 thereon to cause such action. To each of said projections 35, one of two yokes 37 is connected, each yoke being pivoted to the machine at 38 and having an arm 39 with a roller 40 thereon operating in one of two cam grooves 41 on the cam 120 member 42. This cam member 42 is keyed to a shaft 43 which, in turn, carries a pinion 44 connecting by two gears 45 with a gear 46 on the stub shaft 47, the latter having a beveled gear 48 thereon meshing with a 125 130

beveled gear 49 on the gear 22 which carries the cam 21. It will thus be seen that motion is communicated from the drive shaft 6, through the pinion 22, to the cam 42 which 5 effects the movement of the retaining members 27 toward and from each other on the rock shaft 34.

The movement of the rock shaft 34 to carry the retainers with the member 26 toward and from the carrier or die plate 7 is 10 effected, in this instance, by an eccentric 50 arranged on the shaft 47 and operating in a strap 51, the latter having a pitman rod 52 guided therein to bear at its inner end 15 against the eccentric 50. This pitman rod is pivotally and adjustably connected at 53 with an arm 54 on the rock shaft 34. When the eccentric 50 rotates or turns, the retaining devices or members 27 will, assuming 20 that they are in the position shown in full lines in Fig. 6, be swung to the position shown in dotted lines in the same figure. On their return movements, under the action of the coil spring 56, the retaining devices will 25 be stopped by a stop or abutment 55 on the frame, thus causing the eccentric 50 and its strap 51 to proceed on their movements independently of the pitman 52, so that a dwell may take place in the movement of 30 the retaining device 27, notwithstanding the continuous movement of the eccentric 50. Later on the eccentric will engage the inner end of the pitman 52 and shift the retaining devices away from the carrier or die 7.

35 The operation of the machine will be understood from the foregoing description, but may be summarized as follows:

The articles to be pressed are placed in the pocket 8 which is next to move under the 40 press element 2. The article which had been previously subjected to said element is carried over the primary ejector or plunger 19 which is then elevated to eject the article X from the pocket 8 and present it against the 45 member 26 of the secondary ejector. About this time the retainers 27 move under the article and form a chute, and then the chute swings with the shaft 34 as an axis to discharge the article to one side of the machine. 50 The primary ejector returns to its initial position under the action of the spring 20 after the article is engaged by the retainers, and the latter separate after the discharge of 55 the article to be in positions to pass under the next article upon the return of the secondary ejector to the position where it will receive the article from the primary ejector.

50 What I claim as my invention and desire to secure by Letters Patent is:—

60 1. An ejecting mechanism comprising an ejecting plunger, and a secondary ejector movable in a direction normal to said plunger and having a member in engagement with which one face of the article is 65 moved by the plunger and also having re-

taining means engaging opposite edges of the article while the latter is held against the member by the plunger.

2. In combination with a movable carrier having pockets, a primary ejector movable 70 through said pockets to discharge the articles therefrom, and a secondary ejector receiving said articles from the primary ejector and carrying the same away from the primary ejector.

75 3. In combination with a carrier having pockets and means for moving the carrier step-by-step, a primary ejector, means for projecting the primary ejector through one of the pockets while the carrier is stationary, 80 a secondary ejector for moving the articles away from the primary ejector, and a spring for returning the primary ejector to its initial position to permit the carrier to bring another pocket to the primary ejector.

85 4. In combination with a rotary carrier plate having pockets therein, means for moving the carrier step-by-step, a plunger, a revolving cam arranged to project the plunger through the successive pockets while 90 the carrier is stationary, a spring for returning said plunger to its initial position, and a secondary ejector for receiving the articles from the plunger and carrying them away from said plunger.

95 5. In combination with a stationary and a movable press member, a rotary die plate arranged to carry articles between the press members and then away from said members, said die plate having pockets therein, means 100 for imparting a step-by-step movement to the die plate, a plunger ejector arranged to be projected through said pockets after the latter have passed out of coöperation with the two press members, a rotary cam 105 mounted to turn loosely on the shaft of the die plate and adapted to project the plunger through a pocket when the die plate is stationary, and a spring for returning the plunger to initial position.

110 6. An ejecting mechanism comprising a primary ejector, a secondary ejector for receiving articles from the primary ejector, the secondary ejector being mounted to swing and having a portion against which one face of the article is pressed by the primary ejector, retaining members movable to coöperate with opposite edges of the article while it is held by the primary ejector against the secondary ejector, and means for 115 swinging the secondary ejector away from the primary ejector after the retaining devices have engaged the article.

120 7. An ejecting mechanism comprising a primary ejector, and a secondary ejector, the latter having two retaining devices each forming a chute section adapted to pass under an article held by the primary ejector to conduct an article away from the primary ejector.

8. In combination with a stationary and a movable press member, a rotary die plate arranged to carry articles between the press members and then away from said members, 5 said die plate having pockets therein, means for imparting a step-by-step movement to the die plate, an ejector arranged to be projected through said pockets after the latter have passed out of coöperation with the two 10 press members, and a chute movable under the article held by the ejector to receive said article and to conduct it away from said ejector.

9. An ejecting mechanism comprising a 15 primary ejector and two chute sections movable toward each other to pass under the article held by the primary ejector to conduct such article away from the primary ejector.

10. An ejecting mechanism comprising a 20 primary ejector and two chute sections movable toward each other to pass under the article held by the primary ejector to conduct such article away from the primary ejector, said chute sections being pivotally mounted 25 to turn about a common axis extending transversely of the sections.

11. In an ejecting mechanism, the combination with a primary ejector, of a 30 secondary ejector including two chute sections mounted to turn about an axis transversely of the sections, mechanism for moving said sections toward each other to cause them to pass beneath the article on the primary ejector and away from each other after 35 the article has been discharged by the chute, and mechanism for moving the chute sections about their axis to cause them to swing to an inclined position to discharge the articles and to return to the primary ejector 40 prior to the movement of the chute sections beneath another article.

12. In an ejecting mechanism, a primary 45 ejector, a secondary ejector having retaining devices for passing beneath the articles on the primary ejector, and means for

swinging the secondary ejector to cause the latter to discharge the articles received from the primary ejector, said means having provision for permitting the secondary ejector to dwell in its swinging action while the retaining means is passing beneath the articles. 50

13. In an ejecting mechanism, a primary ejector, a pivotally mounted secondary ejector having retaining devices for removing the articles from the primary ejector, means 55 for swinging the secondary ejector comprising an eccentric, a strap surrounding said eccentric, a pitman slidably in said strap and connected to the secondary ejector at a point eccentric to the pivotal axis of said ejector, 60 and means for stopping the secondary ejector while the retaining devices are receiving an article from the primary ejector.

14. In an ejecting mechanism, the combination with a primary ejector, and a pivotally mounted secondary ejector embodying a rock shaft, two retaining members secured to the shaft to turn therewith and movable toward and from each other on the shaft to receive the article from the primary ejector, 70 of means for rocking the shaft and for producing a dwell in said rocking while the retaining devices are receiving an article from the primary ejector, and means for moving said retaining members longitudinally of the 75 rock shaft.

15. In an ejecting mechanism, the combination with a primary ejector, of a secondary ejector adapted to receive articles 80 from the primary ejector, and comprising two retaining members movable toward and from each other to pass under the article while the latter is held by the primary ejector, two crossed levers pivotally and 85 slidably connected at their ends to the retaining members, and a member supported by the crossed levers and adapted to coöperate with the upper face of an article on the primary ejector.

MICHAEL W. O'BRIEN.
